Specification of Letters Patent.

Patented Oct. 21, 1913.

Application filed April 14, 1910. Serial No. 555,514.

To all whom it may concern:

Be it known that I, GEORGE J. B. RODWELL, a subject of the King of Great Britain, residing at Buffalo, in the county of Erie and State of New York, have invented certain new and useful Improvements in Signs, of which the following is a full, clear, and exact description, such as will enable others skilled in the art to which it appertains to make and use the same.

This invention relates to signs, display devices and articles of like nature.

A general object is to provide a simple and inexpensive device of the above type which shall attract and hold attention.

Another object is to provide a practical device of the above character in which letters or symbolic characters of any desired configuration may be formed in such manner as to produce strong contrast between portions thereof and to have artistic appearance.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing wherein are shown various possible embodiments of my invention, Figure 1 is a front view of a letter comprising certain features of this invention; Fig. 2 is a cross section taken on line $x-x$ of Fig. 1, looking in the direction indicated by the arrows; Fig. 3 is a front view of a portion of a sign showing a single letter, the facing view being broken away to bring out more clearly an important feature of the invention. Fig. 4 is a front view of a portion of a sign showing a plurality of symbolic characters, the same being a modification of the invention. Fig. 5 is a cross-sectional view of another embodiment of the invention.

Similar reference characters refer to similar parts throughout the several views.

Preliminary to a description of the inven-

tion it may be noted that in devices of the nature of those with which this invention deals, it is desirable that the lettering or other design be prominent and stand out as clearly as possible from the surrounding surface. This is best accomplished by making this part appear luminous, either by means of light from an independent source transmitted through the same or by means of reflecting or diffusing the light cast on the outer surface thereof. The latter is the simpler and more economical course but the reflecting surface if unprotected may be obscured by a natural accumulation thereon. Best results are attained when the face of a letter has a slightly roughened light diffusing surface in strong contrast with certain other brilliantly reflecting surfaces. Signs made in accordance with the present invention are well adapted to attain the above results.

Referring now to Fig. 1 of the drawings, there is represented by 1 a character, that illustrated being the letter "G," which comprises a piece of sheet metal die-pressed to provide a plane marginal portion 2 and a convex depressed portion 3. Between the edges of said depressed portion and said marginal portion there extends an outwardly flaring portion 4 which is given a bright reflecting surface. The stamping is so carried out that sharp lines 5 form the boundaries of the said depressed portion. This depressed portion forms the face of the letter and is covered with a coating 6 of paint or a similar substance which is flowed upon the convex surface thereof, the sharply defined edges 5 enabling said paint to form a coating having a clear outline. While the paint is still wet finely powdered glass or other glassy substance is sprinkled thereon and when dry, the surface formed thereby is one not only well adapted to diffuse light, but by reason of the irregular faces provided by the glass, to produce an effect whereby the attention of the passer-by is instantly attracted. Instead of painting the face portion 3 and then powdering with glass, the effect produced by the irregular surfaces of the glass may be in part obtained by corrugat-

ing or indenting the surface of said portion and then applying a coat of gilt to both said face and the inclined portion 4. Another advantage of a surface of this character is that the letter, or other character or device, 5 may be seen from a much greater distance than is the case when a smooth regular surface is employed. In order that the letter or character may be fully protected, and 10 having in mind the further object of causing the same to stand out clearly and distinctly, the letter is mounted upon the back of a transparent facing, preferably a glass plate, 15 as 7, and is affixed thereto in any desired manner. A portion of the plate surrounding the letter has a coating of some opaque substance 8, as black or dark colored paint, applied thereto, as shown in Fig. 3. The paint forms a border surrounding the letter 20 and extends inwardly beneath the same to the inner edge of the marginal portion thereof. It is to be understood that any number of these characters or letters may be applied to the back of the facing plate and arranged 25 to constitute any desired word or symbol. When a plurality of letters are employed it is convenient to stamp the metal in one piece containing the whole of the reading matter and the glass is stenciled leaving the letters 30 or other characters clear, and the rest of the ground work in black or in various other colors adapted to produce the desired effect, (Fig. 4). The metal letters are then matched 35 on the portions of the glass stenciled, after which the whole is secured in a frame in any desired manner. In the latter construction the entire back of the plate is covered 40 with the opaque substance with the exception of those parts thereof located within the inner edges of the marginal portions of 45 said letters. And although these letters or characters may be formed of any suitable material, sheet brass has been found to have many advantages when used in this connection. The outwardly flaring portion 4 may 50 be left in its natural color, but is preferably gilded. It is believed that the best effect is produced by having the opaque portions black, the central face portions white, with 55 clear powdered glass, or corrugated and gilded, and the intermediate outwardly flaring portions finished brightly in gilt.

The method of use of the invention herein described will be obvious, but it may be noted that the application of the same is extremely broad and in no wise limited to the form of sign herein described.

As many changes could be made in the above construction and many apparently 60 widely different embodiments of this invention could be made without departing from the scope thereof as set forth in the appended claims, it is intended that all matter contained in the above description or shown in 65 the accompanying drawings shall be inter-

preted as illustrative and not in a limiting sense.

Having described my invention, what I claim as new and desire to secure by Letters Patent is:

1. A symbolic character comprising, in combination, a marginal portion, a sharply defined inner face portion depressed below said marginal portion and connected therewith by an outwardly flaring portion, and a coating on said face portion adapted to diffuse light and appear in strong contrast with said other portions. 70

2. A symbolic character comprising, in combination, a marginal portion, a sharply defined inner face portion depressed below said marginal portion and connected therewith by an outwardly flaring portion, and a coating on said face portion comprising a fine glassy substance. 80

3. A symbolic character or letter comprising, in combination, a plane marginal portion, a convex central face portion, said face portion being depressed below said marginal portion and connected therewith by an outwardly flaring portion, a reflecting coating applied to said flaring portion, and means covering said face portion adapted to diffuse light and to appear in strong contrast with said other portions. 85

4. A symbolic character or letter comprising, in combination, a plane marginal portion, a convex central face portion, said face portion being depressed below said marginal portion and connected therewith by an outwardly flaring portion, and a coating applied to said face portion adapted to appear in strong contrast with said other portions. 100

5. A symbolic character or letter comprising, in combination, a plane marginal portion, and a convex central face portion, said face portion being depressed below said marginal portion and connected therewith by an outwardly flaring portion, said face portion being covered with paint and a comminuted glassy substance. 105

6. In an advertising sign, in combination, a glass facing, a plurality of characters each comprising a plane marginal portion, a depressed central portion and an outwardly flaring portion connecting said other two portions, said characters being affixed to the back of said glass with the said marginal portion lying flatly thereagainst, an opaque substance applied to said back and extending beneath said characters to the inner edges of the marginal portions thereof, a brilliantly reflecting coating applied to said outwardly flaring portion, and a dull diffusing coating applied to said central portion, whereby said last portion is made to appear in strong contrast with said other portions. 115

7. A symbolic character comprising in combination, a plane marginal portion, a central face portion, said face portion being 125

depressed below said marginal portion and connected therewith by an outwardly flaring portion, said face portion being provided with irregular reflecting surfaces and
5 with an applied coating, and a coating applied to said flaring portion, whereby said last portions appear in strong contrast with said marginal portion.

In testimony whereof I affix my signature, in the presence of two witnesses.

GEORGE J. B. RODWELL.

Correction in Letters Patent No. 1,076,519.

It is hereby certified that in Letters Patent No. 1,076,519, granted October 21, 1913, upon the application of George J. B. Rodwell, of Buffalo, New York, for an improvement in "Signs," an error appears in the printed specification requiring correction as follows: Page 1, line 40, strike out the word "view"; and that the said Letters Patent should be read with this correction therein that the same may conform to the record of the case in the Patent Office.

Signed and sealed this 28th day of October, A. D., 1913.
